UNITED STATES PATENT OFFICE.

MORRIS H. BENNETT, OF WATERBURY, CONNECTICUT, ASSIGNOR TO SCOVILL MANUFACTURING COMPANY, OF WATERBURY, CONNECTICUT, A CORPORATION OF CONNECTICUT.

VARIABLE CONDENSER.

Application filed December 1, 1926. Serial No 151,864.

This invention relates to improvements in variable condensers and more particularly to condensers used in radio receiving sets.

One object of this invention is to provide a 5 variable condenser which when assembled in a radio receiving set will produce most efficient results.

In circuits used in radio receiving sets where several stages or steps of amplification 10 are employed, each of which is tuned, it is difficult during manufacture to maintain the relation of wires, parts, etc., to such accuracy as to have each circuit of the same distributed capacity.

15 It is a feature of this invention to provide improved means for adjusting the capacity of these circuits to the same value, the construction being such that no additional loss will be introduced into the radio frequency 20 circuit. To this end, there is provided an auxiliary condenser plate which is mounted on the frame in the bushing which is usually provided for the terminal connection of the rotor plates.

25 For a full understanding of the invention a detailed description of a construction embodying the same in its most advantageous form will now be given in connection with the accompanying drawings forming a part 30 of this invention and the features forming the invention will then be pointed out in the appended claims.

In the drawings—

Figure 1 is a rear view of a variable condenser embodying the invention;

Figure 2 is a top plan view thereof; and

Figure 3 is a section taken along the line 3—3 of Fig. 2.

Referring specifically to the drawings, 40 there is shown, for purposes of illustration, a variable condenser comprising a front side 1 and a rear side 2 secured in spaced relation to each other by standards 3. To obtain the advantage of interchangeability these standards 45 are similar in construction and have flat surfaces to provide a larger bearing face and to be better adapted to support insulating blocks 4, 4^a. However, the edges of the standards 3 may be rounded and their ends 50 reduced to project through holes pierced through each corner of sides 1 and 2. The ends of these standards are turned down for riveting to the sides and thus securing the standards and sides together to form a frame.

Side 1 has a suitably located opening 5 of 55 such size that the handle end 6 of rotor shaft 7, which may be of insulating material, may be positioned in said opening.

A plate 8 having an opening of such size that it closely fits over end 6 of shaft 7 covers 60 any excess of opening in side 1 and be secured in said side by screws threaded into posts 9, hereinafter referred to. The plate 8 also constitutes a support for the end 6 of shaft 7. This plate 8 is so shaped that it 65 does not project beyond the edges of side 1. Side 1 is also provided with a plurality of perforations to receive studs 10 threaded to receive screws for securing the condenser to the usual panel board to which such condensers are attached, either in vertical or horizontal position. The rear ends of these studs are turned down securely against side 1. Plate 12 is secured to the inner side of side 1, in any suitable manner as by posts 9, the 70 inner ends of which posts are turned down to take against plate 12, their outer ends being secured by screws passing through such posts and also through cover plate 8. Plate 12 is also provided with a flanged opening of such 75 size that it allows shaft 7 with its sleeve 11, after the plates 13 have been secured thereon, to pass through, the flange thereof conforming, in shape and size, substantially to that of the cone-shaped end of sleeve 11 to form 80 a cone type bearing for such shaft and sleeve. The plate 12 is made of resilient material 85 spaced by posts 9 so as to act as a spring to press against the cone end of the sleeve 11, preventing play in the rotor while allowing 90 the latter to turn smoothly.

Sleeve 11 carries a set of rotor plates 13 each rotatable between two plates of a set of stator plates 14, rigidly fixed in blocks 15, 16. Shaft 7 is provided with a suitable bearing 95 17 which is preferably adjustable in side 2 as shown.

A terminal binding post 18, threaded to receive the usual securing nuts, is provided on blocks 4 and 4^a for the stator plates. Connection is made from the sleeve 11, holding the rotor plates, by means of a pigtail 19 to a metallic bushing 20 having an internal bore 26, said bushing extending through an opening in the rear side 2, and being supported 100 by suitable insulating washers 22, 23.

Preferably the capacity adjustment comprises a metallic disk 24 which may, if de-

sired, be provided with a covering of dielectric, such as mica, and has a central boss 25 adapted to extend into the bore 26 of bushing 20.

5 The position of disk 24 may be axially adjustable by means of a cap screw 27 threaded into the boss 25. The turning of screw 26 into boss 25 causes disk 24 to approach bushing 20. Reverse movement of disk 24 is effected by 10 turning screw 26 in the opposite direction. A spring 28 maintains the parts in proper relation. Rotation of disk 24 is prevented by splining boss 25 and the walls of bore 26, as shown at 29 and 30. The contact plate 31, 15 having an upturned finger 32 for receiving the usual connecting wire, surrounds and contacts with bushing 20, being held in place by a lock washer 33.

After the condenser has been assembled and 20 mounted in an amplifying circuit of a radio set, adjustment of the zero value of the condenser may be made by tuning the circuit to receive a signal at or near the zero capacity of the condenser. The rotor plates are then in 25 their zero position. Auxiliary plate 24 is now moved toward or away from outermost stator plate 34 by simply turning screw 27 out of or into boss 25 until the volume of signal received is a maximum.

30 When one or more condensers are connected in amplifying circuits in a radio set, the latter is tested and adjusted. This is accomplished by adjusting the set to receive a signal near the zero capacity of the condensers. As 35 shown, adjustment of plate 24 is made to a position in which the maximum signal strength is received, spring 28 maintaining the parts in their adjusted position. After all the condensers in the receiving set have 40 been similarly adjusted and secured there will be provided a radio set having balanced capacity in all its circuits.

By utilizing the same insulation that is needed to hold the supporting bushing for 45 the pigtail connector to the rotor plates it is

evident that no additional loss will be introduced into the circuit by this construction.

What is claimed is:

1. A condenser comprising a set of stator plates, a set of rotor plates, an insulated terminal connection for said rotor plates, an auxiliary element mounted on said connection, means to adjust said element initially with respect to one of said stator plates, and means to hold said element in adjusted position. 50

2. A condenser comprising a frame, a set of stator plates, a set of rotor plates, a bushing constituting an insulated terminal on said frame and connected to said set of rotor plates, an auxiliary element carried in said bushing and adjustable with respect to one of said stator plates, and a spring for holding said element in adjusted position. 60

3. In a condenser, and in combination, a set of stator plates, a set of rotor plates, said plates being mounted to interleave so that the stator plates are outside, a bushing, a flexible connecting lead from said rotor plates to said bushing, a terminal connector carried by said bushing, an auxiliary plate carried by said bushing and parallel to one of said stator plates, screw means to adjust said plate with respect to said stator plate, and means for holding said plate in adjusted position. 65

4. In a condenser, and in combination, a set of stator plates, a set of rotor plates, said plates being mounted to interleave so that the stator plates are outside, a bushing, a flexible connecting lead from said rotor plates to said bushing, a terminal connector carried by said bushing, an auxiliary plate having a central boss, a bore in said boss threaded to receive an adjusting screw, said bushing being centrally bored to receive said boss, splines on said boss to prevent rotation thereof, and a spring acting upon said boss. 80

In testimony whereof, I have hereunto set my hand.

MORRIS H. BENNETT.
